UNITED STATES PATENT OFFICE

FRANZ LANG, OF MUNICH, GERMANY, ASSIGNOR TO ACRO AKTIENGESELLSCHAFT, OF KUESSNACHT AM RIGI, SWITZERLAND

INTERNAL COMBUSTION ENGINE

Application filed April 19, 1929, Serial No. 356,423, and in Germany June 28, 1928.

The present invention relates to internal combustion engines of the type operated by the injection of liquid fuel which is self-ignited and wherein the compression chamber is divided into three portions, firstly the cylinder chamber, secondly a mixing chamber and in free communication with the cylinder chamber, into which the fuel is injected, and thirdly a chamber which is connected 10 with the mixing chamber solely by a throttling orifice.

In such engines the third chamber acts as an air reservoir into which air is forced during the compression stroke and then flows 15 during the combustion through the throttling orifice into the mixing chamber where it supplies the combustion air.

In certain known engines of the type described, the throttling orifice consists of a single narrow port. It has however also been proposed to divide the throttling orifice into a plurality of ports. These proposals do not however detail the relative location of the 25 individual ports.

According to the present invention, the throttling orifice is divided into a main port and at least one auxiliary port, the mouth of which is directed into the mixing chamber 30 so that the current flowing out of the same meets the jet of fuel at a different point and a different angle from the current emerging from the main port. A considerably better admixture of the fuel with the air is obtained 35 in many cases in this manner than is possible with only one wide main port without any auxiliary ports.

Two forms of construction of the invention by way of example are shown in the 40 accompanying drawings in which:—

Figure 1 is a longitudinal section through the cylinder and piston in one form of construction in which the auxiliary chamber is located in the piston.

Figure 2 is a longitudinal section through the cylinder and piston of a modified form of construction in which the auxiliary chamber is provided in the cylinder head.

Figure 3 is a plan view of a detail of Figure 2.

In the first form of construction shown in Figure 1, the actual cylinder is indicated by *a*, the piston reciprocating therein by *b*, the cylinder head by *c* and the injection nozzle and holder by *d*. The piston is hollowed out on the side opposite the cylinder head and a bell-shaped shell *e*, the open face of which is covered by a cover *f*, is provided in the recess. The shell and cover are held in position by a covering ring *g* screwed on to the piston.

The compression chamber is divided into three portions. It is composed of firstly, the cylinder chamber *h*, the volume of which varies during the movement of the piston, second, a frusto-conical mixing chamber *i* located in the cover *f* and in free communication with the cylinder chamber, and thirdly a chamber *k* defined by the shell and the cover. This is permanently connected with the mixing chamber by a narrow port *m* and also by a plurality of narrow auxiliary ports *n*. The narrowest part of the auxiliary ports is at the point where they open into the mixing chamber.

The operation of the engine described is as follows:—

After the fuel injected into the funnel chamber *i* in the proximity of the top dead centre has commenced to burn, the air forced out of the cylinder chamber into the auxiliary chamber by the piston during the compression stroke flows through the main port *m* and the auxiliary ports *n* back into the mixing chamber and there assists the combustion. The orifices of the auxiliary ports in the mixing chamber are so positioned that air emerging therefrom meets the jet of fuel injected through the nozzle *d* at a different point and a different angle from the current emerging from the main port.

In this manner intimate and rapid admixture of the air with the fuel and consequently smokeless combustion is obtained.

The ducts of the auxiliary ports follow a straight course. The axes thereof intersect at a point located on the axis of the cylinder. The auxiliary ports are symmetrically positioned.

A notable feature of the first form of construction is that better evacuation of the auxiliary chamber is obtained by means of the auxiliary ports than was possible with a suitably enlarged main port as the air which is located in the portion *o* of the chamber located above the dotted line—therefore as regards the main ports in a "dead space"—can escape through the auxiliary ports.

10 The main difference between the second form of construction and the first is the arrangement of the auxiliary chamber which is provided in the cylinder head instead of in the piston. Corresponding elements are indicated by the same reference numerals as in Figure 1.

15 The only difference in operation in the second form of construction is that a resultant blowing effect is obtained by the symmetrical arrangement of the auxiliary ports which forces the flame formed in the mixing chamber *i* against the cylinder wall so that the parts surrounding the mixing chamber 20 are not to strongly heated.

25 The number of auxiliary ports and the shape of the same is of no importance for the realization of the invention. On the other hand, however, it is important that the total cross section of the ports including the main port should always exceed a definite minimum.

I claim:

1. An internal combustion engine comprising in combination a cylinder forming a main compression chamber, an element having a truncated conical opening, the narrow end of which lies remote from said main compression space, an auxiliary compression chamber on the opposite of said narrow end of said truncated conical space communicating with said truncated space by auxiliary passages in said element at an angle to the sides of the conical space therein and an injection nozzle adapted to project fuel through part of said main compression chamber into said conical space.

2. An internal combustion engine comprising in combination a cylinder forming a main compression chamber, an element having a truncated conical opening, the narrow end of which lies remote from said main compression space, an auxiliary compression chamber on the opposite of said narrow end of said truncated conical space communicating with said truncated space by auxiliary passages in said element at an angle to the sides of the conical space therein, the narrowest cross section of which is at the point 40 at which they open into said conical space, and an injection nozzle adapted to project fuel through part of said main compression chamber into said conical space.

3. An internal combustion engine comprising in combination a cylinder forming

a main compression chamber, an element having a truncated conical opening, the narrow end of which lies remote from said main compression space, an auxiliary compression chamber on the opposite side of said narrow end of said truncated conical space, the remote corners of which communicate with said truncated space by auxiliary passages in said element at an angle to the sides of the conical space therein and an injection nozzle 75 adapted to project fuel through part of said main compression chamber into said conical space.

4. In an internal combustion engine having a main compression chamber and an auxiliary compression chamber, a member provided with a truncated conical passage connecting said chambers, said member being provided with an auxiliary passage extending from said auxiliary compression chamber to said truncated conical passage.

5. An internal combustion engine having a main compression chamber and an auxiliary compression chamber connected by a mixing chamber tapering toward said auxiliary compression chamber, said mixing chamber also being connected to said auxiliary compression chamber by an auxiliary passage tapering toward said mixing chamber.

6. An internal combustion engine of the self-ignition type having a main compression chamber and an auxiliary compression chamber connected by a truncated conical mixing chamber tapering toward said auxiliary compression chamber, said mixing chamber 100 being provided with a throttling constriction where it opens into said auxiliary compression chamber, and an injection nozzle adapted to project fuel through part of said main compression chamber into said mixing 105 chamber, said mixing chamber also being connected to said auxiliary compression chamber by a plurality of auxiliary ducts.

7. An internal combustion engine as set out in claim 6 in which the auxiliary ducts 110 are unsymmetrically arranged.

In testimony whereof I have hereunto affixed my signature.

FRANZ LANG.
